(57) **CLAIM**

I claim the ornamental design for a tessellating board, as shown and described.

DESCRIPTION

FIG. 1 is a top view of one embodiment of a tessellating board of the present general inventive concept;

FIG. 2 is a front view of the tessellating board of FIG. 1;

FIG. 3 is a rear view of the tessellating board of FIG. 1;

FIG. 4 is a left side view of the tessellating board of FIG. 1;

FIG. 5 is a right side view of the tessellating board of FIG. 1;

FIG. 6 is a bottom view of the tessellating board of FIG. 1;

FIG. 7 is a top view of another embodiment of a tessellating board of the present general inventive concept;

FIG. 8 is a front view of the tessellating board of FIG. 7;

FIG. 9 is a rear view of the tessellating board of FIG. 7;

FIG. 10 is a left side view of the tessellating board of FIG. 7;

FIG. 11 is a right side view of the tessellating board of FIG. 7;

FIG. 12 is a bottom view of the tessellating board of FIG. 7;

FIG. 13 is a top view of another embodiment of a tessellating board of the present general inventive concept;

FIG. 14 is a front view of the tessellating board of FIG. 13;

FIG. 15 is a rear view of the tessellating board of FIG. 13;

FIG. 16 is a left side view of the tessellating board of FIG. 13;

FIG. 17 is a right side view of the tessellating board of FIG. 13;

FIG. 18 is a bottom view of the tessellating board of FIG. 13;

FIG. 19 is a top view of another embodiment of a tessellating board of the present general inventive concept;

FIG. 20 is a front view of the tessellating board of FIG. 19;

FIG. 21 is a rear view of the tessellating board of FIG. 19;

FIG. 22 is a left side view of the tessellating board of FIG. 19;

FIG. 23 is a right side view of the tessellating board of FIG. 19; and,

FIG. 24 is a bottom view of the tessellating board of FIG. 19.
